CLAIM

The ornamental design for a torchiere floor lamp substantially, as shown and described.

DESCRIPTION

FIG. 1 is a perspective view of a torchiere floor lamp of the present invention;

FIG. 2 is a front elevational view thereof;

FIG. 3 is a rear elevational view thereof;

FIG. 4 is a right side view thereof;

FIG. 5 is a left side view thereof; and,

FIG. 6 is a top view thereof.

The dash-dot lines in FIGS. 1–6 indicate a translucent surface.

The surfaces(s) or portion(s) of the article not shown in the drawing or described in the specification form(s) no part of the claimed design.
